UNITED STATES PATENT OFFICE.

ERNEST STOECKLIN, OF RIDGEFIELD PARK, NEW JERSEY.

TOOL-HOLDER.

1,022,760.

Specification of Letters Patent.

Patented Apr. 9, 1912.

Application filed May 17, 1911. Serial No. 627,752.

To all whom it may concern:

Be it known that I, ERNEST STOECKLIN, a citizen of the United States, and resident of Ridgefield Park, in the county of Bergen 5 and State of New Jersey, have invented a new and useful Improvement in Tool-Holders, of which the following is a specification.

My invention relates to tool holders and is more particularly directed to boring tool 10 holders for engine lathes, the object being to provide a holder in which the tool may be rapidly and easily brought into any desired position in a rotative direction and to any desired position in a longitudinal direction 15 within certain limits and clamped in such position.

My invention further contemplates means for holding tools of various sizes and character.

20 A practical embodiment of my invention is represented in the accompanying drawings, in which—

Figure 1 represents in top plan a portion of the slide rest of a lathe with my invention 25 proved holder mounted thereon with a tool carried thereby, portions of the tool bar being broken away to more clearly illustrate the means for clamping the cutter in position, Fig. 2 is an end view of the part 30 shown in Fig. 1, Fig. 3 is a section taken in the plane of the line A—A of Fig. 1, and Fig. 4 is a section taken in the plane of the line B—B of Fig. 2.

The slide rest of the lathe is denoted by 35 1 and its longitudinally arranged undercut slot by 2. The tool holder comprises an outer member in the form of a split ring 3 and an inner member in the form of a divided bushing, one part being denoted by 40 4 and the other part by 5. This divided bushing is rotatably adjustable in the split ring and it is provided with tool receiving holes 6 extending longitudinally therethrough, one portion of each hole being located with 45 45 in the part 4 and the other portion in the part 5. In the present instance I have shown six of these holes in an annular series, the said holes being of varying sizes and the walls between the adjacent holes 50 being cut away to form slots 7 for permitting the withdrawal of the tool in either direction when the tool is released from its clamping engagement with the bushing, as will hereinafter more fully appear. This 55 divided bushing 4, 5, is provided with a circumferential groove 8. A clamping bolt

9 has its head 10 fitted to slide in the undercut slot 2 of the lathe, which bolt extends upwardly through the free ends of the ring 3 and it is provided with a nut 11. This 60 bolt 9 intersects the periphery of the divided bushing 4, 5, by entering the circumferential groove 8 in the bushing for holding the bushing against longitudinal movement within the clamping ring 3 while permitting the bushing to be rotated within 65 said clamping ring when released from its clamping engagement therewith. These tool receiving holes 6 may receive tools of various kinds. In the present instance I 70 have shown a large size boring tool in position within the largest of the holes 6, which tool is constructed as follows:—A hollow tool bar 12 is provided with aligned diagonal holes 13, 14, through its walls at 75 one end of the bar for receiving the cutter 15. At its other end, the said hollow bar 12 is provided with aligned holes 16, 17, through its walls at right angles to the bar 80 for receiving the cutter 15 when the position of the bar is reversed. The bore of the bar 12 is screw-threaded as shown at 18 at both 85 of its ends for receiving a clamping screw 19.

A rod 20 is interposed between the inner 90 end of the screw 19 and the cutter 15 so that as the screw 19 is screwed inwardly against one end of the bar 20 the other end of the said bar will engage the cutter 15 and clamp it rigidly in its adjusted position.

In operation: After the tool has been inserted into the divided bushing, the bushing is adjusted rotatively and the tool is adjusted both rotatively and longitudinally to bring its cutter 15 into the desired position 95 with respect to the work to be operated upon. The nut 11 is then screwed inwardly drawing the free ends of the clamping ring 3 toward each other and drawing the clamping ring into snug engagement with the slide rest 1 thus serving to draw the parts of the divided bushing into clamping engagement with the tool for clamping the tool in its adjusted position and drawing the ring 3 into snug engagement with the divided bushing for clamping the bushing in its adjusted position and for drawing the rings also into snug engagement with the slide rest for clamping the holder in position on the slide rest.

100 It will thus be seen that a single bolt 105 serves to accomplish three purposes, the 110

clamping of the outer member of the holder to the slide rest, the clamping of the inner member of the holder to the outer member, and the clamping of the tool within the inner member. It will also be seen that by this arrangement the cutting edge of the tool may be adjusted to any desired rotative or longitudinal position within prescribed limits by a very simple and effective means.

10 While I have shown this invention as applied to a boring tool holder for engine lathes, it is to be understood that I do not wish to limit myself to the particular structure and application herein shown but contemplate its use wherever applicable and also that I do not wish to limit myself strictly to the construction of the parts herein shown and described, but

What I claim is:—

- 20 1. A tool holder comprising a split outer member, a rotatably adjustable inner member having a plurality of tool receiving holes therethrough, said inner member being divided through said holes and means
25 for clamping the inner member to the outer member in any of its rotative adjustments.

2. A slide rest, a tool holder mounted thereon comprising a split outer member, a tool holding divided inner member rotatably adjustable in the outer member and a 30 bolt arranged to clamp the inner member to the outer member and the outer member to the slide rest.

3. A slide rest, a tool holder mounted thereon comprising a split outer member, a 35 tool holding divided inner member rotatably adjustable in the outer member and a bolt arranged to clamp the inner member to the outer member and the outer member to the slide rest, the said bolt intersecting the 40 periphery of the divided inner member for holding it against longitudinal movement within the outer member.

In testimony, that I claim the foregoing as my invention, I have signed my name in 45 presence of two witnesses, this twentieth day of April 1911.

ERNEST STOECKLIN.
